[57] CLAIM

The ornamental design for a storage unit for a van or the like, as shown and described.

DESCRIPTION

FIG. 1 is a front perspective view from above of one embodiment of a storage unit for a van or the like according to our new design;

FIG. 2 is a rear perspective view from below of FIG. 1; FIG. 3 is an end elevation view of FIG. 1;

FIG. 4 is a front perspective view from above of a second embodiment of a storage unit for a van or the like according to our new design;

FIG. 5 is a rear perspective view from below of FIG. 4;

FIG. 6 is an end elevation view of FIG. 4;

FIG. 7 is a front perspective view from above of a third embodiment of a storage unit for a van or the like according to our new design;

FIG. 8 is a rear perspective view from below of FIG. 7;

FIG. 9 is an end elevation view of FIG. 7;

FIG. 10 is a front perspective view from above of a fourth embodiment of a storage unit for a van or the like according to our new design;

FIG. 11 is a rear perspective view from below of FIG. 10;

FIG. 12 is an end elevation of FIG. 10;

FIG. 13 is a front perspective view from above of a fifth embodiment of a storage unit for a van or the like according to our new design;

FIG. 14 is a rear perspective view from below of FIG. 13;

FIG. 15 is an end elevation view of FIG. 13.
